UNITED STATES PATENT OFFICE.

WARREN A. ROSS, OF LONG BEACH, CALIFORNIA, ASSIGNOR OF ONE-FOURTH TO DONALD M. CARTER, OF CHICAGO, ILLINOIS, AND ONE-FOURTH TO TRUMAN O. BOYD, OF LONG BEACH, CALIFORNIA.

DRILLING DEVICE.

Application filed January 22, 1927. Serial No. 162,719.

This invention relates to drilling devices and has for its object to provide a new and improved object of this description.

The invention has as a further object to provide a simple and effective construction by means of which a series of cutters may be used and may be automatically fed to the material to be cut as they are worn away.

The invention has as a further object to provide an arrangement of cutters whereby the automatic feed of the cutters may be insured.

The invention has other objects which are more particularly pointed out in the accompanying description.

Referring, now, to the drawings:

Fig. 1 is a view in part section showing one form of device embodying the invention.

Fig. 2 is an enlarged bottom view of the device shown in Fig. 1.

Fig. 3 is a sectional view taken on line 3—3 of Fig. 2.

Fig. 4 is a sectional view, with parts broken away, taken on line 4—4 of Fig. 2.

Fig. 5 is a sectional view taken on line 5—5 of Fig. 2, with parts omitted.

Fig. 6 is a sectional view taken on line 6—6 of Fig. 5.

Fig. 7 is a sectional view taken on line 7—7 of Fig. 2.

Fig. 8 is a sectional view taken on line 8—8 of Fig. 7.

Fig. 9 is a face view of a portion of the holding piece shown in Fig. 8.

Fig. 10 is a view of the upper end of one of the cutters.

Fig. 11 is a sectional view taken on line 11—11 of Figs. 1 and 3.

Fig. 12 is a sectional view taken on line 12—12 of Fig. 1.

Fig. 13 is a view showing the push member and the cutters separate from the other mechanism.

Fig. 14 is an enlarged view, with parts broken away, showing the torque member.

Fig. 15 is a view in part section showing the construction of the lower end of the core barrel.

Fig. 16 is a sectional view taken on line 16—16 of Fig. 15.

Fig. 17 is a sectional view taken on line 17—17 of Fig. 14.

Fig. 18 is a sectional view showing one form of cutter.

Fig. 19 is a sectional view showing a different form of cutter.

Fig. 20 is a sectional view showing a further modified form of cutter.

Fig. 21 is a view showing a further modified form of cutter.

Like numerals refer to like parts throughout the several figures.

The present device may be used for drilling oil wells or wherever it is desired to form an opening. I have illustrated the invention in connection with an oil well drilling apparatus.

In Fig. 1, I have illustrated the lower end of the rotating part or drill pipe 1 by means of which the cutters hereinafter mentioned are rotated. Surrounding this drill pipe is a casing 2. The core barrel is provided with a shoulder 3 which engages a cutter feeding member 4. This cutter feeding member is shown separate from the rest of the apparatus in Fig. 13 and has connected therewith, the cutters 5.

In the construction shown, elongated cutter bits or cutters 5 have their ends 6 bent as shown in Fig. 3 and the cutter feeding member 4 is provided at its lower end with inclined slots into which these inclined ends 6 of the cutters are received. The drill pipe is rotated by any of the usual mechanisms and some suitable means is provided for insuring the rotation of the cutters and the cutter feeding member.

As herein shown, this result is secured by providing the lower end of the drill pipe with longitudinal projections 7, (see Figs. 1, 15, and 16). These projections are received in longitudinally extending grooves 8 in the torque member 9, located within the cutter feeding member and projecting beyond said member and are connected with the drill head 10. This arrangement permits the drill pipe to be slid along the torque member without interfering with the rotation of the torque member, thus permitting the cutter feeding

member to be fed forward to feed the cutters to the material to be cut.

The cutters 5 work in grooves 11 in the torque member so as to be properly confined, 5 and slide along these grooves as they are fed to the material, and so as to be rotated by the torque member.

There is a space 12 between the casing 2 and the torque member 9 into which the cutter 10 feeding member slides as the cutters are fed forward.

The casing 2 is connected with the torque member 9 near the bottom thereof in any suitable manner as by means of the threads 13, 15 on the casing, and the threads 14 on the torque member. The torque member 9 is connected with the drill head 10 in any suitable manner as by means of the threads 15, on the torque member, and the threads 16 on the drill head. 20 The cutters 5 pass through openings in the drill head and are projected therefrom as they are fed to the material to be acted upon.

The holes in the drill head for the cutters, are bent away from the vertical so that the 25 cutting ends of the cutters strike the material to be cut at an angle to the vertical. This arrangement insures the proper projection and feed of the cutters at all times and prevents the cutters from being fed too rapidly 30 and from projecting too far from the drill head. The cutters are flexible so that they can be thus bent.

In view of the difficulty of making these holes in the drill head for the cutters, I may 35 provide grooves therein and then fill up the portions of these grooves not occupied by the cutters, with filling pieces which may be fastened to the drill head in any desired manner as by welding, brazing or the like.

40 I have illustrated in the drawings, certain forms of this construction. Some of the ends of the cutters will be differently positioned circumferentially from others. I have illustrated three series of these differently positioned ends, as shown in Fig. 2, consisting of the ends 17 near the outer edge of the drill head, also shown in Fig. 7, and the ends 18 near the inner face of the drill head, also shown in Fig. 3, and the intermediate ends

45 19, also shown in Fig. 5. For the openings for the ends 17, I provide a groove 20, (see Fig. 8), and a filling piece 21 which is provided with a groove 22 for the cutter. For the intermediate cutter ends 19, I may provide a large groove 23 (see Fig. 6) and a smaller groove 24 the proper size for the cutter and then provide a filling piece 25 for the groove 23.

It will be noted that in one case, the opening 60 for the cutter is formed in the filling piece and in the other case, it is formed in the drill head itself, but in each case, the filling piece, when properly fastened in position, properly confines the cutter. The slots or openings for 65 the cutters in the lower part of the torque

member are closed by a ring 26 against which abuts the casing 2, (see Figs. 1, 3, and 4). This ring 26 is shrunk or welded to the torque member. The cutters are made flexible so that they will bend when sufficient pressure 70 is applied to them and pass around the bent openings in the drill head. These cutters may be made flexible in various ways.

They may, for example, be made of steel, hardened and then annealed so as to soften 75 the exterior thereof. This provides a cutter with a very hard center or core and a soft exterior surrounding the hard core. The proportion of the hard core or center to the soft exterior or outer casing will depend, of 80 course, upon the conditions presented.

I have illustrated in Fig. 18, a cross section of one of these cutters showing the soft exterior or casing 5^a and the hard center or core 5^b. The outer covering or casing will 85 bend without breaking and will hold the hard core or center in position even though it should break into pieces. This permits the use of the hard center for cutting and prevents the cracking or breaking of the core 90 from interfering with the cutting effect. The cutter may be made of a wire cable pressed into the desired shape and bound together in any desired manner, as by a coating of lead.

95 In Fig. 19, I have shown a sectional view of such a cutter having the wires 5^c and the binding material 5^d of lead or other soft material. The cutter may also be laminated, that is, made of several pieces 5^e, held together by a binding material 5^f, as shown in Fig. 20.

In Fig. 21, I have shown a sectional view of a cutter having a central portion or core 5^g surrounded by a coat 5^h of a hard material 105 such as chromium. In this construction, the central portion or core is soft and the outer coating is hard. In any of these constructions the cutters are flexible enough so that they may be bent at their ends as shown in 110 Fig. 3. I may also use any ordinary material soft enough to be thus bent but cutters of this type will not wear as long as the foregoing forms of cutters.

115 In my construction, the cutters are straight and are fed forward as they are worn off at the ends, straight portions of the cutters being successively bent laterally as they are fed to the material to be acted upon, that is, as the ends are worn off. This feeding and bending is done during the cutting process and is done automatically responsive to the wearing away of the ends of the cutters and the cutters are flexible enough to permit this bending during the feeding process. The 120 cutting ends of the cutters are bent laterally at the desired angle, such angle being such that they can be projected only a small distance from the drill head regardless of the pressure applied to their upper ends. This 125

angle is such that the ends wear off at substantially right angles to the body portion, as shown in Fig. 3 and I have found that the bending of these ends to the proper angle, as the cutters are fed forward, is essential to the successful operation and successful automatic feeding of the device, and further for the prevention of a too great projection of the ends of the cutters from the 10 drill head.

It will further be noted that the cutters are provided with a confining device which confines the straight portions thereof so that they will not bend or warp due to the pressure of the feeding member and the rotating part.

When the device is used for oil wells and the like, the usual means for removing the cuttings may be employed. For example, a 20 removing fluid may be passed down the opening in the drill pipe and will pass up around the casing carrying with it the material cut loose by the cutters in the usual manner. It will be noted that the drilling device includes a holder with guideways adjacent the outer end thereof and elongated cutting bits having their outer ends slidably disposed in said guideways, there being means cooperating with said guideways for 25 feeding the bit outwardly, and simultaneously bending the outer portions thereof. It will further be noted that the openings in the drill head as shown in the drawings are bent and that the cutting bits are slidably disposed therein and that these openings or 30 guideways act to bring about resistance to the sliding of the cutting bits therein, which resistance is overcome by a pressure-applying device applied to the cutting bits to cause 35 a sliding or feeding movement of the cutting bits to feed them to the material to be cut. When the device is used as a core drill, the 40 drill head 10 is provided with a central opening to receive a core.

45 The use and operation of my invention are as follows:

When the parts are assembled, the straight cutters are placed in position between the casing 2 and the torque member 9 being connected with the feeding member 4. The device is inserted in the hole and the pressure of the 50 rotating part 1 forces the feeding member 4 toward the drill head 10 forcing the ends of the cutters into the passageways in the drill head, the ends projecting a short distance therefrom.

As the device is rotated, the cutters cut away the material and are gradually worn off and the feeding device moves them along so 55 as to successively, during the operation of cutting, force straight portions of the cutters into the inclined openings in the drill head, thereby successively bending straight portions in said cutters laterally during the feeding process, and this continues until the feed-

ing member reaches the limit of its downward movement.

The bending of the ends of the cutters makes it impossible to force the ends thereof out to too great an extent, the ends only projecting from the drill head a short distance. The bending of the ends of the cutters is the thing that prevents a too great projection of the cutters from the drill head. As the ends of the cutters are worn away, the feeding device moves the cutters forward so as to maintain the proper projection of the ends thereof from the drill head.

It will, therefore, be seen that this device acts like a diamond drill without the use of 80 diamonds and by using material cutters. It will further be seen that a great depth of the hole may be secured by one set of cutters before they become worn out thus making it unnecessary to change the cutters often.

I have found that the cutters wear off very slowly and will last a long time and that a hole of uniform diameter may be drilled with this device. The angle at which the ends of the cutters are bent will depend upon the conditions present and I have found that good results are secured by an angle between 25° and 45°. By means of this device, the hole drilled can be maintained at a constant diameter as the cutter material is replaced at just 90 the same distance from the center of rotation during the full life of the cutters, that is, the wearing off and feeding of the cutters does not, in any manner, interfere with securing 95 this constant diameter of the hole drilled. 100 This device, therefore, insures against the tapering of the hole.

I claim:

1. A drilling device comprising a rotatable member, a casing into which said rotatable member projects, a torque member slidably connected with said rotatable member so as to rotate therewith, a drill head connected with said torque member and having passageways extending therethrough, a plurality of cutters 110 intermediate the casing and the torque member and extending into said passageways in said drill head, a feeding member interposed between the casing and the torque member and adapted to move said cutters to cause the ends thereof to project from said drill head.

2. A drilling device comprising a rotatable member, a casing into which said rotatable member projects, a torque member slidably connected with said rotatable member so as to 120 rotate therewith, a drill head connected with said torque member and having passageways extending therethrough, a plurality of cutters intermediate the casing and the torque member and extending into said passageways 125 in said drill head, a feeding member interposed between the casing and the torque member and adapted to move said cutters to cause the ends thereof to project from said drill head, the upper portions of said cutters being 130

straight, the passageways in the drill head being bent laterally so that portions of said cutters as they are forced therein are bent at an angle to the straight portions of said cutters.

5. 3. A drilling device comprising a rotatable part, a casing into which said rotatable part slidably projects, a torque member in said casing slidably connected with said rotatable member, a plurality of cutters located between the casing and the torque member, a feeding member adapted to feed said cutters forward, means for moving said feeding device, said cutter slidably mounted in straight guideways, a drill head connected with said torque member and provided with passageways which connect with said guideways, the passageways in the drill head being bent laterally so as to bend the ends of the cutters laterally with relation to the remaining portion thereof, as the cutters are fed therein.

4. A drilling device comprising a rotatable part, a casing in which said rotatable part slidably projects, a torque member slidably connected with said rotatable part but rotatable therewith, a feeding member between said casing and said torque member and adapted to be moved forward by said rotatable part, a series of cutters located between the casing and the torque member, said cutters having their ends removably fastened to said feeding member, said cutters sliding in straight confining guideways, a drill head connected with said torque member and casing and provided with passageways which connect with said guideways in which the cutters slide, said passageways being bent laterally at an angle to said guideways so that they bend the ends of the cutters laterally with relation to the remaining portions thereof as the cutters are forced therein.

5. A drilling device comprising a rotatable part, a casing into which said part slidably projects, a torque member feathered to said rotatable part so as to slide with relation thereto, a feeding member intermediate said casing and said torque member and adapted to be moved forward by said rotatable part, a series of cutters located between said casing and said torque member and connected with said feeding member, said torque member being provided, on its exterior, with grooves in which said cutters slide, and a drill head connected with said torque member and said casing and provided with passageways having their inner ends in alignment with said grooves, a portion of said passageways bent laterally so as to be out of alignment with said grooves.

6. A drilling device comprising a rotatable part, a casing into which said part slidably projects, a torque member feathered to said rotatable part so as to slide with relation thereto, a feeding member intermediate said casing and said torque member, and adapted to be moved forward by said rotatable part, a

series of cutters located between said casing and said torque member and connected with said feeding member, said torque member being provided, on its exterior, with grooves in which said cutters slide, and a drill head connected with said torque member and said casing and provided with passageways having their inner ends in alignment with said grooves, a portion of said passageways bent laterally so as to be out of alignment with said grooves, the outer walls of the grooves in the drill head being formed by filling pieces separate from said drill head but fastened thereto.

7. A drilling device comprising a rotatable part, a casing into which said rotatable part slidably projects, a series of cutters on the interior of the casing, guideways in which said cutters are slidably confined, said cutters being fed forward by the forward movement of said rotating part, a drill head connected with said casing through which said cutters extend, and means for successively bending portions of said cutters laterally as such portions are moved into said drill head.

8. A drilling device comprising a series of cutters, a feeding device for feeding them forward as the cutting ends are worn off, and means for successively bending portions of said cutters near the cutting ends thereof as they are fed forward to feed them to the material.

9. A drilling device comprising a series of flexible cutters straight for a portion of their length, a confining device therefor from which the ends of the cutters are projected as they are worn in cutting the material, and means for successively bending straight portions of said cutters laterally while they are being fed forward to the material to be cut.

10. A drilling device comprising a series of cutters, said cutters each consisting of hard material and soft material arranged so that the cutters may be bent while being used, guideways in which said cutters are slidably disposed having portions thereof out of alignment with other portions thereof, and means co-operating with said guideways for feeding said cutters outwardly and simultaneously bending them.

11. A drilling device including a holder with a guideway adjacent the outer end thereof, an elongated cutting bit having its outer end slidably disposed in said guideway, and means cooperating with said guideway for feeding said bit outwardly and simultaneously bending the outer portions thereof.

12. A drilling device including a holder with a series of guideways adjacent to the outer end thereof, a series of elongated cutting bits having their outer ends slidably disposed in said guideways, and means cooperating with said guideways for feeding said cutting bits outwardly and simultaneously bending the outer portions thereof.

13. A core drilling device including a holder having a central opening to receive a core and provided with a guideway adjacent the outer end thereof, an elongated cutting bit having its outer end slidably disposed in said guideway, and means cooperating with said guideway for feeding said bit outwardly and simultaneously bending the outer portion thereof.
14. A core drilling device including a holder having a central opening to receive a core with a series of guideways adjacent to the outer end thereof, a series of elongated cutting bits having their outer ends slidably disposed in said guideways, and means cooperating with said guideways for feeding said cutting bits outwardly and simultaneously bending the outer portions thereof.
15. A drilling device including an elongated cutting bit, a holder with a guideway adjacent to the outer end thereof in which said cutting bit is slidably received and which acts to bring about resistance to the sliding of said cutting bit therein, and a pressure-applying device for automatically applying pressure to said cutting bit during the operation thereof, to overcome the resistance to its sliding movement in said guideway, to automatically feed the cutting bit to the material to be cut.
16. A core drilling device including an elongated cutting bit, a holder therefor having a central opening to receive a core and provided with a guideway adjacent the outer end thereof in which said cutting bit is slidably received and which acts to bring about resistance to the sliding of said cutting bit therein, and a pressure-applying device for automatically applying pressure to said cutting bit during the operation thereof, to overcome the resistance to its sliding movement in said guideway to automatically feed the cutting bit to the material to be cut.
17. A drilling device including a series of elongated cutting bits, a holder with a series of guideways adjacent the outer ends thereof in which said cutting bits are slidably received and which act to bring about resistance to the sliding of said cutting bits therein, and a pressure-applying device for automatically applying pressure to said cutting bits during the operation thereof, to overcome the resistance to their sliding movement in said guideways to automatically feed the cutting bits to the material to be cut.
18. A core drilling device including a series of elongated cutting bits, a holder having a central opening to receive a core and being provided with a series of guideways adjacent the outer ends thereof in which said cutting bits are slidably received and which act to bring about resistance to the sliding of said cutting bits therein, and a pressure-applying device for automatically applying pressure to said cutting bits during the operation thereof, to overcome the resistance to their sliding movement in said guideways to automatically feed the cutting bits to the material to be cut.
19. A drilling device including a drill pipe, a series of cutting bits operatively connected with said drill pipe, a drill head, confining means for said cutting bits throughout that portion of their length above said drill head, said drill head being provided with openings into which portions of said cutting bits are received and which act to produce a resistance to the forward feeding movements of said cutting bits, and a pressure-applying device for automatically applying pressure to said cutting bits during the operation thereof, to overcome said resistance due to said openings and automatically feed said cutters to the material to be cut.
20. A core drilling device including a drill pipe, a series of cutting bits operatively connected with said drill pipe, a drill head, having a central opening to receive a core, confining means for said cutting bits throughout that portion of their length above said drill head, said drill head being provided with openings into which portions of said cutting bits are received and which act to produce a resistance to the forward feeding movements of said cutting bits, and a pressure-applying device for automatically applying pressure to said cutting bits during the operation thereof, to overcome said resistance due to said openings, and automatically feed said cutters to the material to be cut.
21. A core drilling device comprising a rotatable member, a casing into which said rotatable member projects, a torque member slidably connected with said rotatable member so as to rotate therewith, a drill head having a central opening to receive a core connected with said torque member and having passageways extending therethrough, a plurality of cutters intermediate the casing and the torque member and extending into said passageways in said drill head, a feeding member interposed between the casing and the torque member and adapted to move said cutters to cause the ends thereof to project from said drill head.
22. A core drilling device comprising a rotatable member, a casing into which said rotatable member projects, a torque member slidably connected with said rotatable member so as to rotate therewith, a drill head having a central opening to receive a core connected with said torque member and having passageways extending therethrough, a plurality of cutters intermediate the casing and the torque member and extending into said passageways in said drill head, a feeding member interposed between the casing and the torque member and adapted to move said cutters to cause the ends thereof to project from said drill head, the upper portions of

said cutters being straight, the passageways in the drill head being bent laterally so that portions of said cutters as they are forced therein are bent at an angle to the straight 5 portions of said cutters.

23. A core drilling device comprising a rotatable part, a casing into which said rotatable part slidably projects, a torque member in said casing slidably connected with said 10 rotatable member, a plurality of cutters located between the casing and the torque member, a feeding member adapted to feed said cutters forward, means for moving said feeding device, said cutters slidably mounted 15 in straight guideways, a drill head having a central opening to receive a core connected with said torque member and provided with passageways which connect with said guideways, the passageways in the drill head being bent laterally so as to bend the ends of the 20 cutters laterally with relation to the remaining portion thereof, as the cutters are fed therein.

24. A core drilling device comprising a rotatable part, a casing in which said rotatable part slidably projects, a torque member slidably connected with said rotatable part but rotating therewith, a feeding member between said casing and said torque member and 30 adapted to be moved forward by said rotatable part, a series of cutters located between the casing and the torque member, said cutters having their ends removably fastened to said feeding member, said cutters sliding in 35 straight confining guideways, a drill head having a central opening to receive a core connected with said torque member and casing, and provided with passageways which connect with said guideways in which the cutters slide, said passageways being bent laterally at an angle to said guideways so that 40 they bend the ends of the cutters laterally with relation to the remaining portions thereof as the cutters are forced therein.

45 25. A core drilling device comprising a rotatable part, a casing into which said part slidably projects, a torque member feathered to said rotatable part so as to slide with relation thereto, a feeding member intermediate 50 said casing and said torque member and adapted to be moved forward by said rotatable part, a series of cutters located between said casing and said torque member and connected with said feeding member, said 55 torque member being provided, on its exterior, with grooves in which said cutters slide, and a drill head connected with said torque member and said casing and provided with passageways having their inner ends in alignment with said grooves, a portion of said 60 passageways bent laterally so as to be out of alignment with said grooves.

65 26. A drilling device comprising a movable member having a series of guideways, elongated cutting bits slidably disposed in

said guideways, a feeding member provided with a series of receiving spaces for said cutting bits and by means of which the cutting bits are attached to the feeding member, the position of the cutting bits being controlled 70 by said feeding member.

Signed at Chicago, county of Cook and State of Illinois, this 20th day of January, 1927.
